Primary Examiner — Deanna L Pratt(57) **CLAIM**

The ornamental design for a makeup mirror, as shown and described.

DESCRIPTION

FIG. 1 is a perspective view of a makeup mirror showing my new design;

FIG. 2 is another perspective view thereof;

FIG. 3 is a perspective view of the makeup mirror where the make up mirror is in a close state;

FIG. 4 is a front elevational view of FIG. 1;

FIG. 5 is a rear elevational view of FIG. 1;

FIG. 6 is a left side elevational view of FIG. 1;

FIG. 7 is a right side elevational view of FIG. 1;

FIG. 8 is a top plan view of FIG. 1; and,

FIG. 9 is a bottom plan view of FIG. 1.

The broken lines in the drawings depict portions of the makeup mirror that form no part of the claimed design.
